UNITED STATES PATENT OFFICE

JOHN F. DONOVAN, OF EAST CLEVELAND, AND FRANK J. MALLOY, OF CLEVELAND, OHIO, ASSIGNORS TO GENERAL ELECTRIC COMPANY, A CORPORATION OF NEW YORK

BULB SHAPING DEVICE

Application filed May 11, 1929. Serial No. 362,420.

Our invention relates to machines for the manufacture of electric incandescent lamps and other electrical devices comprising sealed containers and more particularly to machines for shaping said sealed containers adjacent to the seals thereof to receive bases. The object of our invention is to provide automatically operating mechanism which may be used as an attachment, for instance, 10 for a sealing-in machine which, as is well known in the art, is used for sealing mounts into the bulbs of incandescent lamps and similar articles. Our invention includes means for accurately positioning the bulb 15 for the operation of the shaping or shoulder forming mechanism. Another feature of our invention is the provision of safety devices to prevent breakage. Various other features and advantages of our invention will appear from the following description of a species thereof and from the accompanying drawings.

In the drawings, Fig. 1 is a perspective view of the machine of our invention shown 20 in conjunction with a lamp sealing-in machine; Fig. 2 is a plan view of the upper lamp centralizing jaws; Fig. 3 is a plan view of the lower centralizing and shoulder forming jaws with their operating mechanism; Fig. 25 4 is a view of the lamp in the sealing-in machine with the shoulder forming jaws in operative relation thereto; Fig. 5 shows an automatic safety disconnecting device including a plan view of the electrical contact making apparatus and a partially diagrammatic view of the remaining parts; Fig. 6 is a side elevation of the operating mechanism for one of the contacts of the disconnecting device; Fig. 7 is a side elevation of the disconnecting key and co-acting parts of this device; Fig. 8 is a perspective view of a lever and related parts used as a supplemental safety feature; and Fig. 9 is a perspective view of the shoulder forming jaws in associated relation.

Our machine is shown as a part of an apparatus which seals the stem of an incandescent lamp to the bulb. The sealing machine consists of a number of heads mounted 50 on a carrier which indexes to the right. A

lamp in each head rests loosely in a holder 25 (Figs. 1 and 4). The shoulder forming machine first accurately positions the lamp, then forms the shoulder. The vertical position of the lamp is fixed by a ring 24 which 55 clamps the lamp in the bulb holder 25 while the shoulder forming process is being performed. Its horizontal position is fixed by a pair of upper jaws 32 and 33 and also by a set of three lower jaws 42, 43, and 44 60 which close around the bulb neck. After the lamp is positioned, the three shoulder forming jaws 45, 46 and 47 close around the seal portion of the bulb neck which is in a semi-molten state and form the shoulder. This 65 leaves the lamp with a shoulder similar to that shown in Fig. 4.

As shown in Fig. 1, our machine is operated through the lever 10 which is driven from a cam on the main cam shaft of the 70 sealing machine and swings back and forth to give a reciprocating motion to the slide 16. When the slide 16 has reached its forward position, as determined by the striking of its extension bracket 15 against an adjustable stop pin 17 (Fig. 8) which is fastened to the stationary frame 18, springs 12 allow lever 10 and bar 11 which is slotted for pin 13 to complete their full movement. The main slide 16 carries sub-slide 19 which 75 moves with slide 16 until the pin 20 carried thereby strikes against the stationary pin 21. Block 22 fastened to sub-slide 19 is attached to springs 23 which tend to keep it against slide 16. The extent of movement of the various jaws depends on the difference of movement of these slides 16 and 19. 80

The bulb centering cup 24, as shown in Figs. 1 and 4, exerts a slight pressure on the top of the bulb causing it to remain in a fixed relation to the bulb holder 25 during the complete shoulder forming operation. After 85 sub-slide 19 becomes stationary, the continued movement of slide 16 carrying cam 26 lifts roller 27 which indirectly moves arm 28.

This arm draws part 29 and with it bushing 30 down, giving spring 31 tension enough to keep the bulb in its proper position. The bulb's position horizontally is set by the 90 upper centralizing jaws 32 and 33 shown in 100

Figs. 1, 2 and 4. These jaws, as shown in Figs. 1 and 2, are operated when lever 34 pivoting on arm 35 fastened to stationary sub-slide 19 is forced down by the cam 36. The lever 34 (Fig. 2) operates arm 37 and consequently bar 38 by means of the springs 39. The forward movement of bar 38 operating through the toggle action shown, closes the jaws. Movement of part 38 and therefore the position of the jaws is regulated by the striking of part 38 against adjusting screw 40 (Fig. 1) carried by the sub-slide 19. The lower jaws 42, 43 and 44 used for centering are made in three sections and carry the shoulder forming jaws 45, 46 and 47, having overlapping meeting edges as shown in Fig. 9, to prevent the formation of ridges in the glass which might arise from the use of straight edge jaws. These jaws, as shown in Fig. 3, are forced together by the forward movement of slide 16. One jaw is mounted directly on this slide and the others on two arms 48 and 49. These arms pivot at 50 and 51 on the sub-slide 19 and are swung apart at one end by the cams 52 and 53. The springs 54 and 55 attached to arms 48 and 49 and to sub-slide 19 pull the jaws apart as the slide 16 withdraws. In Fig. 1 a head of the sealing machine and the lamp supported thereby are shown as they arrive at the shoulder forming position after having been indexed through the sealing-in fires (not shown) leaving the bulb neck at the seal portion thereof in a semi-molten state. During the sealing-in operation the lamp holder has been rotated by belt 56 which engages pulley 57 so as to allow uniform heating of the seal portion. It is important that the head be properly positioned for the shoulder forming operation as it has parts which would otherwise interfere with those of the shoulder forming machine as they advance and close around the lamp. Means are provided for stopping the rotating head in a definite position and for rendering the shoulder forming means inoperative until the head is in proper position. The stopping mechanism and also the mechanism for discontinuing the operation of the shoulder forming machine are shown in Fig. 5. A roller 58 carried by pulley 57 is adapted to be engaged by a lever 59, when the head is in proper position for the shoulder forming operation, to stop the rotation of the head, while the belt 56 slips on the pulley 57. As the head is indexed into position, its rotation continues until this engagement of roller 58 and lever 59 takes place. Meanwhile, as hereinafter explained, the mechanism for closing the shoulder former and other jaws ceases to operate. Spring 60 attached to lever 59 allows the roller 58 to pass as the head is indexed to the right after the shoulder forming process has been completed. Lever 61 is pivoted on lever 59 and serves as a latch to keep the roller from backing away during the shoulder forming operation. When the head is in the correct position, as indicated by the roller, lever 62 which carries contact 64 is swung to a position where contact 65 does not touch contact 64. This contact 65 is mounted on the lever 66 which allows it to be raised or lowered according to the position of the main operating lever 10. As in Fig. 6, lever 66 is connected to the main lever 10 by the rod 67 and the slotted bar 68. Slotted bar 68 is so placed that at the full retarded position of main lever 10 pin 69 will pull on bar 68 which indirectly pulls the contact 65 up and out of the plane of the contact 64. Spring 70 draws lever 66 down at all other positions of the main lever 10. Therefore, if roller 58 and consequently the sealing head are not in the correct position, contact 65 will fall on contact 64 closing the circuit, allowing solenoid 71 to operate. The solenoid 71 acting through parts 72 to 76 draws key 77 out of a keyway in bar 14 permitting the bar to slide free in bracket 15. The armature 72 is drawn upward by the solenoid 71 thus forcing rod 73 to rotate shaft 74 by means of the lever 75. As shown in Fig. 7, lever 76 which is keyed to the shaft 74 draws key 77 out of the keyway in bar 14. This action unlocks the operating arm 10 from the machine giving free motion to the arm without operation of the machine. The key 77 is returned to its operating position when solenoid is not operating by the combined action of the spring 78 and the weight 100 of the moving armature 72. Another safety feature is shown in Fig. 8. If for any reason, the closing of the forming jaws is not desired, arm 79 is raised, thus stopping bracket 15 before it has reached its maximum forward position as designated by the pin 17. What we claim as new and desire to secure by Letters Patent of the United States is:

1. A device adapted to shape the neck of a bulb supported vertically in a movably supported holder and having a portion thereof in a plastic condition which comprises a vertically movable cup adapted to engage the top of said bulb, a set of pivoted centering jaws adapted to engage the neck of said bulb, a set of pivoted shaping jaws adapted to engage said plastic neck portion, means for moving said holder and means connected to said cup and to said jaws for reciprocating said cup and opening and closing said jaws in proper time relation to the movement of said holder. 110
2. In a machine of the class described, a shaping device comprising three jaws adapted to fit together to form an annular shoulder, a reciprocatable slide carrying one of said jaws, pivoted arms each carrying one of the other jaws and means actuated by the reciprocation of said slide for causing the said piv- 120
3. Lever 61 is pivoted on lever 59 and serves as 130

oted jaws to close together and with said other jaw when the latter reaches its operative position.

3. In a machine of the class described, the combination of bulb positioning and shaping means comprising a vertically reciprocatable cup, a set of pivoted centering jaws disposed therebelow, a set of movable shaping jaws located below said centering jaws, a horizontally reciprocatable slide and means whereby the reciprocation of said slide causes the said jaws to open and close and said cup to be reciprocated downwardly as said jaws close and upwardly as they are opened.
- 15 4. The combination with a machine comprising an indexing carrier having thereon a rotary holder for a bulb, means for indexing said carrier and means for rotating said holder of a shaping device disposed at one 20 of the index positions of said holder and comprising a reciprocating slide and shaping jaws carried thereby, an actuating means for said slide controlled by said indexing means, means for rendering said actuating means inoperative unless the rotation of said holder 25 has been stopped with the said holder in proper position to allow said shaping jaws to be reciprocated into operative position.

5. In a machine of the class described, the combination of a movable carrier having thereon a bulb holder, means for indexing said carrier, a shaping device mounted adjacent to the path of travel of said holder comprising a reciprocatable slide, connections comprising an arm connected to said slide whereby said slide is actuated in proper time relation to the movement of said carrier and means for disconnecting said arm and slide except when said holder is in proper 40 position comprising members carried by said carrier and shaping device respectively, an electromagnetic device, an electric supply circuit comprising contacts and means controlled by the relative positions of the afore- 45 said members for causing said contacts to engage or separate.

6. In a machine of the class described, the combination of a movable carrier having thereon a bulb holder, means for indexing said carrier, a shaping device mounted adjacent to the path of travel of said holder comprising a reciprocatable slide, connections comprising an arm connected to said slide whereby said slide is actuated in proper time relation to the movement of said carrier and means for disconnecting said arm and slide, a bar carried by said slide, a key mounted to move into and out of a key-way in said bar, electromagnetic means controlling the movements of said key, an electric supply circuit comprising make and break contacts and an operating lever connected to a movable contact, and a projecting member on said bulb holder adapted to operate said lever when the

said projecting member and lever are in proper relative positions.

In witness whereof, we have hereunto set our hands this 9th day of May, 1929.

JOHN F. DONOVAN.
FRANK J. MALLOY.
